UNDERWATER LISTENING AID FOR
SUBMERGED PERSONNELJohn M. Ide, Alexandria, Va. (2332 Massachusetts
Ave., NW, Washington, D.C. 20008)
Filed July 23, 1946, Ser. No. 685,631
5 Claims. (Cl. 340—5)

The invention described herein may be manufactured and used for the Government of the United States of America for governmental purposes without the payment of any royalties thereon or therefore.

This invention relates to methods of and apparatus for underwater direction finding, and more particularly to underwater direction finding by acoustical effects.

Binaural perception of sound in air is well known, and is generally believed to arise from the fact that sounds coming from any direction except straight ahead reach the two ears at slightly different times. In air, the ears can estimate bearings to a few degrees, corresponding to time differences of the order of one-one hundred thousandths of a second. With the ears submerged, the direction of underwater sound should be perceived in the same manner as in air, but the accuracy should be lower owing to the difference in sound velocities in air and water. In water the situation is further complicated by the masking effect of sound received by bone conduction through various parts of the head. Sound received through areas midway between the ears, particularly the top and back of the head, has no directional character but does contribute to the overall loudness.

Investigation has shown that submerged bone conduction hearing and submerged eardrum hearing are of the same order of sensitivity. It may be expected that effects of increasing depth will further attenuate the eardrum hearing sensitivity, owing to the unbalance of static pressure on the drum. Since the bone conduction hearing is not so affected, the directional indication usually arising from a binaural effect becomes progressively lost, and tests have shown that to a submerged person the sound source appears more or less directly overhead at all times. A first object of the present invention is to remedy this, and to restore a binaural effect from which a direction indication may be gained by providing means for acoustical separation of the parts of the head in the region of the ears. A further object is to provide means to this end which will be simple, and light in construction.

A principal feature of this invention is the use of a strip of material having acoustical impedance sharply different from that of the seawater, and in acoustic contact with the central part of the bony structure of the head, in a helmet of light construction closely fitting the head. This and other features of the invention will become more apparent from the following detailed description taken together with the accompanying drawing, wherein the single figure is a perspective of a helmet constructed according to the principles of the present invention.

There is depicted in the figure a helmet of fabric or other light material having portions 10 adapted to extend over and fit the sides of the head, and a centrally disposed portion 11. The portion 11 extends from front to back of the helmet, and when worn will thus extend from the base of the skull to the forehead. The portion 11 forms an outer covering for a sponge rubber strip 12 which provides a sharp acoustic mismatch with the seawater owing to the great number of air bubbles it contains. A piece of fabric or light material 13 is sewed in to form a pocket containing the sponge rubber strip 12. The stitches 14 indicate the line of the sewing. The portions 10 have holes 15 cut through so that the ears may be free. A buckle 16 attached to one side portion 10, and a strap 17, attached to the other side portion 10 and having eyes

2

18 suitably spaced, provided means for securing the helmet to the head of the wearer. The size of the rubber strip 12, while not critical, has been found to affect the effective hearing sensitivity considerably. A substantially uniform width of four inches, with a length which extends from the forehead to the base of the skull, has been found to be adequate.

Any suitable material having a sharp mismatch of acoustical impedance with that of the seawater can be substituted for the sponge rubber. For example, an inflated diaphragm or air cell fitted into the section 11 would have substantially the same effect. The sponge rubber has been found to withstand much use without appreciable deterioration.

15 An example of a direct application of these principles occurs in a system of underwater navigation for swimmers in underwater demolition teams or commando type operations. For beach reconnaissance which must be conducted with a large measure of secrecy, a small boat equipped with a suitable underwater sound source may be positioned in a known location offshore. Swimmers equipped with helmets as herein described are sent forth from the boat, and then are able to locate beach characteristics, obstacles in the approaches, etc., by orientating themselves with respect to the sound source, even though entirely submerged. In addition, this system provides a homing signal for expediting the return of the swimmers to the boat. Interruption or modulation of the sound source may be used as a danger signal or to impart information. 20 Directional properties of an underwater sound source may be used to selectively guide an individual swimmer or group of swimmers "down the beam" in a special angular sector. In this way a special sector of beach may be investigated or obstacles avoided. This 25 has the added advantage of even more security than the non-directional sound source affords. It is easy to see that multiplication of these systems will furnish a method of keeping formation, or of guiding a boat to or from a sound source. Such navigating procedures have been found to 30 be effective despite ocean currents. The inherent simplicity and lightness of the equipment required to effect such operations allow their impromptu and extended performance under a great variety of circumstances.

No attempt has been made here to exhaustively point 45 out or cover all the features or applications of the present invention. Many others than those described will be apparent to persons skilled in the art. The scope of the invention is to be defined in the following claims.

What is claimed is:

50 1. An underwater listening device for submerged personnel, comprising a strip of material having a substantially uniform width and an acoustic impedance lower than that of water arranged to extend fore and aft along the top of the head of a person substantially from the forehead to the base of the skull and limited in its lateral extent to omit coverage of the ears and sides of the head, and means for holding said strip in position.

60 2. A listening aid for underwater navigating personnel comprising a hood of relatively thin light material adapted to be worn on the head and carrying a relatively thick central portion in the form of a thickened strip of material having a sharp mismatch of acoustical impedance with that of water extending fore and aft from the forehead to the base of the skull and extending laterally approximately two inches from the center of the head toward each ear over substantially the entire length of the strip.

65 3. A device for enhancing the underwater binaural hearing of a submerged human observer comprising, isolating means for acoustically damping underwater sound waves at the outer surface of the head of said observer, and positioning means maintaining contact between said isolating means and the head of the observer only over a

narrow continuous central portion of said outer surface from the forehead to the base of the skull which is nearly uniform in width.

4. The device according to claim 3 wherein said isolating means comprises a water resistant solid having at least one pocket of gas trapped therein.

5. The device according to claim 3 wherein said positioning means comprises a hood of lightweight fabric to which the isolating means is attached.
